UNITED STATES PATENT OFFICE.

SIDNEY DAVID INSCHO AND ALONZO CLAY MORSE, OF SHELBY, OHIO.

APPARATUS FOR CHARGING AND DISCHARGING FURNACES.

Application filed February 13, 1928. Serial No. 253,911.

This invention relates to an apparatus for charging and discharging furnaces and is adapted for use in association with furnaces for annealing or heat treatment of metal, or 5 seamless drawn tubing or the like.

It is well known to those skilled in the art of annealing or heat treating various metals that many of the furnaces are charged with metal or metal products and the metal 10 or metal products discharged, when the process is completed, by hand manipulation. This operation requires a considerable amount of labor, time and skill in so doing, as the furnace is charged with the metal or 15 metal products piece by piece and discharged therefrom in the same manner and that the expense of performing said work by hand and time lost is considerable, as the work cannot be done with convenience, efficiency, or 20 the speed desirable in such operations.

It is further well known to those skilled in the art that in leaving the furnace door open to the air for more or less long periods of time, that the heat is dissipated therefrom 25 and that the air entering through the opening oxidizes the metal or metal products charged within the furnace.

It is further well known to those skilled in the art that the various metals or metal 30 products that it is desired to charge the furnaces with are situated or located in different parts of the plant. In charging a furnace or a plurality thereof, it is necessary to trundle or carry the various kinds of metal 35 or metal products to a point in close proximity to the front of the furnace or furnaces for charging the furnaces or in discharging the metal or metal products from the furnace and conveying same to another location.

40 The invention is designed for eliminating the laborious and expensive hand manipulation of the metal or metal products in charging or discharging furnaces and substituting therefor, a power operated apparatus to accomplish the purposes and for carrying out the objects hereinafter mentioned or incident thereto.

45 The primary object of the invention is to construct a power operated apparatus adapted to receive and support metal or metal products, which is provided with means that can be actuated to place or carry same within the interior of a furnace for annealing purposes or the like and means to withdraw 50 the metal or metal products from the interior of the furnace, at the will of the operator.

Another object of the invention is to provide a power operated apparatus that can be actuated at the will of the operator to travel laterally in either direction, so as to provide 60 means of alining the apparatus with the front of a particular furnace, or with each furnace of a series of alined furnaces located in either side of the apparatus.

Another object of the invention is to provide a power operated apparatus that can be operated by mechanical power to charge with metal or the like or discharge it from a furnace or plurality of furnaces from the front 65 end of each of a series of furnaces, thereby 70 conserving and economizing in the space required in the plant for operating the apparatus and installing same.

Another object of the invention is to provide a power operated apparatus that permits the charging or discharging of the metal or the like from a single opening located in front of the furnace, to prevent undue dissipation of the heat within the furnace, excessive admission of air and consequent excessive 75 oxidization of the metal or metal products. 80

Another object is to provide a frame for supporting the parts of the apparatus in performing their functions and in achieving the 85 objects of the invention and to provide means for associating therewith a vertical standard that is adapted by suitable electric wiring to conduct and direct an electric current from a source of supply to the apparatus and controlling mechanism thereof. 90

Another object of the invention is to provide an automatically operated safety means for stopping the apparatus at a pre-determined point of its longitudinal movement in 95 either direction after charging or discharging the metal or the like into or from the furnace.

A further object of the invention is to provide means for connecting reversible motors 100 to impart movement to the charging and discharging apparatus and means for stopping the charging and discharging apparatus at any point of its longitudinal travel in either direction, at the will of the operator. 105

A further object is to provide means for operating the draw bar of the apparatus which is actuated by a solenoid.

Another object of the invention is to provide a charging and discharging apparatus 110 that requires but a minimum opening in the furnace for charging and discharging same,

thereby conserving the heat within the furnace and preventing excessive cooling thereof.

Another object is to design an apparatus of the kind herein described that can be operated for the purpose intended without making it necessary to subject the movable and co-acting parts of the apparatus to the heat within the furnace and deleterious effects thereof.

Another object is to construct a charging and discharging apparatus that does not require any means for elevating and lowering the receptacle preparatory to charging or discharging the furnace.

These and other objects are attained by the mechanism illustrated in the accompanying drawings in which—

Fig. 1 is a plan view of the apparatus, also showing the electric motors and solenoid which are applied thereto for operating same by power.

Fig. 2 is a side elevation of a longitudinal central section of the apparatus and also shows a vertical standard mounted thereon to support the conductors used for the purpose of collecting and directing an electric current from a source of supply to the electric motors and other electrical devices used for the operation of the apparatus.

Fig. 3 is a view of the operating or front end view of the apparatus.

Fig. 4 is a view of the furnace end or rear end view of the apparatus.

Fig. 5 is a cross sectional view of Figure 2 taken on the line 2—2 thereof.

Fig. 6 is a cross sectional view of Figure 2 taken on the line 3—3 thereof.

Fig. 7 is a plan view of the controls for the reversible motors, solenoid and the main switch controlling the source of supply of the electric current.

Fig. 8 is a side elevation of a central longitudinal section of the apparatus and a furnace showing the apparatus in position to be actuated for charging the furnace with metal tubes or the like in sectional lines and in position to be actuated for discharging the metal tubes or the like from the furnace in dotted lines.

Fig. 9 shows a bundle or plurality of tubes or the like with a chain wrapped around the bundle of tubes or the like. The chain being supported for transportation to and from the apparatus by a conventional overhead crane (not shown).

In the drawings the parts of the apparatus have been arranged in operative position, some of the parts being shown bolted together by bolts, screws, rivets or the like and others arranged to be electric or otherwise welded together, as preferred. It will be understood that some bolts, rivets, screws or the like are omitted from the drawings that would be used to connect the parts together so as to permit

the reading of the figures of the drawings more clearly, as the omitted parts form no part of the invention and are used and placed at points in the structure where mechanical skill suggests that they should be used for strengthening purposes.

Attention is also called to the fact that the reversible motors, solenoid and control devices used are of conventional type and are wired for use of an electric current for their operation in a conventional manner; hence their specific detail of construction form no part of the invention.

While the invention may be applied and used in various arts, it is especially adapted to be used in mills for the production of seamless drawn tubes or the like in combination with furnaces for annealing or heat treating.

The embodiment or construction of the apparatus is preferably shown in association with furnaces and in the process of heat treating metal or metal products, especially seamless drawn tubing or the like. Attention, however, is called to the fact that it is not intended to limit its use to tube mills or the like as it may be used for different purposes without departing from the principle of the invention.

In the drawings the invention is shown in its preferred embodiment or construction and is constructed as follows:

95

Foundation or truck.

Reference numerals 1 and 2 indicate rails of a track which are arranged on the floor in spaced apart and in parallel relation to each other and positioned in close proximity to the front of a furnace or moved to a line in sequence with a plurality of furnaces. The apparatus is mounted upon and supported on said rails to provide for lateral movement thereof in either direction.

The frame of the apparatus is supported upon a cross truck member 3 at the rear end and is preferably positioned underneath the frame of the apparatus so as to allow the rear end of the apparatus frame to extend beyond the cross truck member 3 in a longitudinal direction. The front end of the apparatus frame is supported on a cross truck member 4 which is positioned underneath the apparatus frame at or adjacent to its front end. The ends of the cross truck members 3 and 4 preferably extend beyond each side of the frame of the apparatus.

The free ends of the cross truck members are preferably bifurcated as shown at 5, 6, and 7, and 8 to provide clearance for the flanged truck wheels 9, 10, 11, and 12, the shafts of which are journaled in box bearings 7'. The arrangement just described, when the apparatus frame is attached or connected to the cross truck members 3 and 4, provide a foundation for supporting the apparatus frame and also a wheeled truck for the appa-

100

105

110

115

120

125

5 ratus frame that can be moved to travel laterally in either direction, that is to the right or left, when mounted on the rails 1 and 2.

5 *Construction of apparatus frame.*

10 In the preferable construction of a frame for the apparatus longitudinal I-beams 13 and 14 are supported on and secured to the cross truck members 3 and 4 in parallel and spaced relation to each other. Cross I-beams 15, 16 and 17 are attached to webs of the I-beams 13 and 14 by angle iron plates 18 and 19. The number of cross I-beams attached to the longitudinal I-beams 13 and 14 can be 15 varied as desired. Auxiliary longitudinal I-beams 20 and 21 are mounted upon and secured to the cross I-beams 15, 16 and 17. The shorter legs or flanges of the angle irons 22 and 23 are attached to the webs of the auxiliary I-beams 20 and 21 as shown in Figures 5 and 6. Angle irons 24 and 25 are supported upon and attached to the longer legs of the angle irons 22 and 23, but are spaced apart from the edges thereof to provide ways 20 or supporting ledges 26 and 27. Rails 28 and 29 are preferably mounted on and secured to the tops of I-beams 13 and 14 on a plane with the tops of I-beams 20 and 21.

30 *Carriage and extension thereof.*

35 A carriage 30 preferably having a tapered extension 31 made integral therewith is provided. The carriage is provided with outwardly horizontally extending wing portions 32 and 33 which extend over the tops of the I-beams 20 and 21 to movably support the carriage. Preferably interposed between the wing portions 32 and 33 and the top of the I-beams 20 and 21 are wearing plates 34 and 35. The carriage is movably held in engagement with one side of the flanges of the I-beams 20 and 21 by the tapered plates 36 and 37 which overlap same and provide guide-ways for the carriage. The carriage is also 40 provided with a depending narrow or reduced portion 38.

45 *Push and draw bar.*

50 A draw bar 39 is pivotally mounted on the carriage upon a pin 40. One end of the draw bar is provided with an inwardly inclined shouldered portion 41. The body portion of the draw bar is slightly turned upward at the point indicated at 42.

55 An arm 43 is preferably made integral with the draw bar. The portion of the draw bar having the shouldered portion 41 is made slightly heavier than the rear end 44 of the draw bar to hold and maintain the shouldered end portion of the draw bar in normal position as shown in Figure 9 in full lines. To actuate the shouldered end of the draw bar to operative position as shown in dotted lines in Fig. 8, a conventional type of sole-

noid 45 is employed to operate a link mechanism. Movement of the draw bar to operative position is accomplished by the link mechanism which is constructed as follows:

60 A solenoid 45 is provided with a solenoid lever 46 which is pivoted on a pin 47. The longer end from the pin is connected to the armature 48 of the solenoid and its shorter end from the pin is connected to one end of a link 49. The opposite end of the link 49 is connected to one arm of a bell crank 50 which is pivotally mounted on a pin 51. The other arm of the bell crank is connected to one end of a connecting rod 52.

65 The opposite end of the connecting rod is connected to the arm 43 of the draw bar, thereby connecting the armature of the solenoid by a linked mechanism, for operation of the draw bar at the will of the operator. It will be understood that the solenoid is operated by an electric current wired thereto in a conventional manner, through push buttons as shown at 53. The push buttons are actuated to complete or break the circuit. When the magnetic influence of the solenoid is produced in the solenoid, armature 48 of the solenoid is drawn in an upward direction imparting movement to the link mechanism and thereby to the end of the draw bar, tilting it to the position shown in dotted lines in Fig. 8 to engage or in position to engage the aperture in the receptacle.

70 To the free end of the tapered extension 31 of the carriage 30 a pusher 54 is pivotally attached by a pin 55. The pusher is preferably made of an I-beam tapered at its free end, as shown at 56, or provided with a plate 56' slightly turned upward at its end and fitted between the flanges of the I-beam, leaving the end of the plate extending beyond the end of the pusher (not shown on the drawing). The pusher is adapted to be reciprocated by the carriage and is supported on the ways 26 and 27.

75 *Tray or receptacle for metal, metal products, tubes or the like.*

80 A receptacle 57 made of the required dimension is provided and is preferably constructed of a comparatively thin flat sheet of metal and its ends as shown at 58 and 59 (see Fig. 2) are turned up. The receptacle is supported for sliding movement on the tops of rails 28 and 29 and I-beams 20 and 21. Supporting members 60 and 61 are attached to the 85 top of the receptacle in spaced apart relation to each other and the receptacle and are turned up at each end as shown by reference numerals 62 and 63 to hold a bunch or bundle of tubes or the like 64 in place on the receptacle.

90 At an appropriate position at one end underneath the receptacle, a lug 65 is secured and is provided with a groove 66 which conforms with the end 56 of the pusher for en-

gagement therewith. At the opposite end of the receptacle, an opening 67 is provided and is preferably made larger than the shouldered end portion 41 of draw bar.

5 Means for collecting and directing an electric current from a source of supply.

It will be understood that a source of supply of an electric current is located and produced at a convenient place in the plant. The current is preferably conducted through conductor bars 68 and 69 which are supported by the girders and brackets 70 and 71. The conductor bars 68 and 69 are preferably located in close proximity to the front of the furnace or a plurality thereof.

At one side and near the end of the apparatus close to the furnace or furnaces, the following means are employed to conduct the current to the electric motors and other electric devices for controlling and operating same. A vertical standard 72, preferably made of an I-beam, is mounted on one end of the cross truck member 3 and is held in position by angle iron brackets 73 and 74 which are secured to the web of the I-beam and the cross truck member 3. Angle iron braces 75 and 76 are secured to the frame and vertical standard 72 to brace and maintain the vertical standard in upright position and are attached thereto by any well known fastening means.

A block of wood or the like 77 is attached adjacent to the top of the vertical standard and contact members 78 and 79 have their ends bifurcated and are secured to the block 77. The free ends of the contact members are enlarged and are adapted to contact with the contact electric conductor bars 68 and 69, thereby conducting the current through the electric wires 80 which are inclosed in the conduit 81 and conducted to the electric motors and other electric devices for controlling and operating the apparatus.

45 Application of power to the apparatus and control thereof by the electric motor and other devices for moving the apparatus laterally.

50 To move the apparatus laterally in either direction to aline it with a particular furnace or one of a series in sequence, a reversible motor 82 is provided on one end of the cross truck member 4 and extension thereof 5'. A pinion 83 is secured to one end of the motor shaft 84 and meshes with a gear 85 mounted on and secured to a shaft 86 which is journaled in bearings 87 and 88 which are mounted on and secured to the cross truck members 3 and 4.

55 A pinion 88' is mounted on and secured to the shaft 86 and meshes with a gear 89 which is mounted on and secured to a shaft 90 upon which the flanged wheel 10 is mounted. A pinion 91 is mounted on and secured to the

shaft 86 and meshes with a gear 92 which is mounted on and secured to a shaft 93 which carries the flanged wheel 9, thereby imparting positive movement to the flanged wheel 9 in unison with the flanged wheel 10.

70

The above described mechanism connects the truck wheels 9 and 10 for operation to move the apparatus in either direction by manipulating the control lever 94 of the conventional control mechanism 95 to drive the reversible electric motor 82 and rotate the shaft thereof in the direction that will force the apparatus to move or travel on the rails in the lateral direction desired, at the will of the operator. It will be noted that the mechanism just described provides means for alining the apparatus with a particular furnace or a plurality of furnaces located laterally of the apparatus in either direction. The wiring for operating of the reversible motor 82 is conventional and the current is supplied from the source of supply as indicated at 80.

85

Means for imparting a forward or rearward movement to the carriage.

90

A reversible motor 95' is provided and mounted on and secured on one end of the cross truck member 4 in opposed relation to the motor 82. A worm 96 is mounted on a shaft 97 of the motor. The shaft 97 is journaled in a bearing provided in the capped housing 98. The motor shaft 99 of the motor 95' is coupled to the worm shaft 97 by a coupling 100, thereby imparting movement to the worm 96. Bearings 101 and 102 are provided in the housing 98 supporting and journaling a shaft 103 at one end.

95

The other end of the shaft is journaled in depending bearings 104 and 105 which are attached to the I-beams 20 and 21. A worm gear 106 is mounted on and secured to the shaft 103 and meshes with the worm 96 thereby imparting movement to the shaft 103. A roller sprocket wheel 107 is mounted on and secured to the shaft 103 and another sprocket wheel 108 is mounted on and secured to a shaft 109. The shaft 109 is journaled in movable bearings 110 and 111. A chain 112 is connected to the sprocket wheels 107 and 108. The shaft 109 is journaled in movable bearings 110 and 111 for the purpose of adjustment to properly tension the chain.

100

110 The adjustment of the sprocket wheel is accomplished as follows: A screw threaded aperture is provided in the cross brace I-beam 114 and a threaded screw 115 is screwed therein and its end is adapted to abut against a boss 116 of the movable bearings. When the screw is actuated it forces the sprocket wheel lengthwise and tensions the chain as desired. After adjustment it is held in place by a lock nut 116'. The carriage is connected to the roller chain by connecting the depending ears 117 and tongue 117' provided on the carriage to a pin 118 of the roller chain.

115

120

125

130

It will be noted that when movement is imparted to the chain that the carriage can be operated to move forward or back as the reversible motor 95' will operate to move 5 or drive the chain in opposite directions, at the will of the operator, by manipulating the lever 119 of the control 120. A conventional main switch 121 is provided to connect or cut off the current from the source of supply by 10 manipulating the lever 122.

Collection of current for conducting same to the apparatus.

Brackets 123 and 124 are secured to the top 15 of the carriage and their free ends are rounded as indicated at 125 and 126 and depending bracket members 127 and 128 are supported thereby. To the free ends of the bracket members 127 and 128, contact pieces 129 and 20 130 are pivotally attached and the free ends thereof extend over and contact with the longitudinal side contact bars 131 and 132. The side contact bars 131 and 132 are secured at their ends by adjustable hooks 133 which 25 engage apertures provided in the ends of the bars. The contact bars 131 and 132 are also held in place and supported by insulator brackets 134.

A cage 135 is provided for the operator to 30 support the controls and main switch and a seat 136 is provided for the convenience of the operator. The controls and main switch are secured to the cage by brackets 137 or by any other well known fastening means. 35 To stop the movement of the carriage in either direction automatically, a conventional automatic safety stop apparatus is used and attached to the operating end of the charging and discharging apparatus and is 40 constructed as follows:

Construction of stop mechanism.

The shaft 103 has its end reduced and screw threaded as shown at 138. A nut 139 is 45 screwed thereon and is moved thereon back and forth breaking and making the circuit of the current near the end of its travel in either direction at pre-determined points. The circuit is broken when the nut 139 passes 50 beyond the contact member 139' at either end thereof. The contact member 139' is in the electric circuit.

In Fig. 9 a bundle of tubes 64 is shown suspended from a conventional crane that is 55 used in shop practice for transporting bundles or the like from place to place.

A chain 140 is secured to a conventional crane and its end is provided with a hook 141. The chain 142 is connected to the hook 60 by the ring 143. The chain 142 is wrapped around the tubes to support same as shown in Fig. 9 and the tubes are moved by the crane to a position directly over the apparatus, preparatory to depositing same on the receptacle 57 as shown in Fig. 9.

The operation in brief of the apparatus will be described with a special reference to Fig. 8 which shows the carriage pusher and pivotal draw bar in section preparatory to moving the receptacle with tubes or the like 70 thereon into the furnace 165 for annealing or other heat treatment. Fig. 8 also shows the receptacle 57 and the pusher and part of the draw bar within the furnace in dotted lines and in a position to withdraw or pull 75 the receptacle with the tubes thereon from the interior of the furnace.

The front end of the furnace is provided with a conventional sliding door (not shown) 80 which is raised to permit the furnace to be charged with tubes, metal products or the like and is closed during the annealing or heat treating process. The floor of the furnace is provided with a plurality of rails 166 spaced apart from each other to provide a 85 support within the furnace for the receptacle 57.

In the spaces between the rails at a lower elevation fire bricks or the like are laid. Preparatory to charging the furnace, a plurality 90 of tubes 64 are gathered into a bundle or the like as shown in Figure 9 from any location in the plant and transported to a position over the receptacle 57 and deposited thereon as shown in Fig. 8.

The control lever 94 of the control 95 is then manipulated to drive the reversible motor 95' in a direction that will force the pusher to travel forward toward and into the open end of the furnace as shown in Figure 8. The tapered end of the pusher as it moves forward engages the groove 66 of the lug 65 and forces the receptacle 57 to travel toward and into the furnace over the rails 166 to the position shown in dotted 100 lines within the furnace. The draw bar 39 being in normal position as shown in Figure 8 in full lines, the control lever 94 of the control 95 is then manipulated to drive the motor in the opposite direction and the 105 pusher and carriage is moved to slide back to its initial or normal position on the frame as shown in section in Figure 8.

When it is desired to withdraw the receptacle 57 and the metal products, tubes or the like deposited thereon after being subjected to heat treatment or annealing, the lever 94 of the control 95 is manipulated to cause the draw bar and other associated mechanism to travel forward part way into the furnace, so 110 that shouldered portion 41 of the draw bar 115 will substantially align with the opening 67 in the receptacle 57.

One of the push buttons 53 is then manipulated to cause the armature 48 of the solenoid to be subject to the electric and magnetic influences of the current and the armature 48 is then drawn in an upward direction actuating the link mechanism which is connected to the armature and to the arm 43 of the draw 120 125 130

bar, thereby forcing the draw bar to tilt upwardly through the opening 67 in a position to engage the receptacle 57.

The control lever 94 of the control 95 is then manipulated to drive the reversible motor 95' in a direction to cause the chain to carry or drive the carriage, draw bar and other associated mechanism to its normal or initial position. The chain 142 is then wrapped around the tubes or the like passing in the space 167 which is provided between the top of the receptacle and bottom of the tubes which are supported upon the rails 60 and 61 for the purpose of providing means for wrapping the chain around the tubes or the like and also to permit circulation of the heat and air around the metal products.

When it is desired to move the apparatus in a sidewise or lateral direction to align same with another furnace or for other purposes the reversible motor 82 is made to rotate in the direction that it is desired to move the apparatus in by the manipulation of the lever 119 of the control 120. The manipulation of the control levers 94 and 119 of the controls 95 and 120 change the rotation of the reversible motors and provide for forcing the apparatus to travel in the lateral direction that it is desired to move same in and align with a furnace or plurality of furnaces in sequence.

Attention is called to the fact that in the operation of the mechanism for charging and discharging the furnace that the mechanism thereof is operated through the medium of the controls, but if for any reason, the operators should inadvertently omit to actuate the mechanism to stop it near the end of its travel in either direction, provision is made, as stated, for automatically stopping same at either end of its travel by the stop mechanism hereinbefore referred to.

Attention is called to the fact that the preferred application of power for operating the charging and discharging apparatus is by and through electric motors and auxiliary electric devices and controls. The apparatus can be operated for the purpose intended by the application of other power, as for instance by compressed air, gas or gasoline motor or steam engine or from power transmitted directly from a line shaft or the like without deviating from the principle involved in the invention described herein; hence, we do not desire to be limited to the application of power by electric motors.

We claim:

1. In a charging and discharging apparatus for a furnace, a frame mounted for lateral movement in front of the furnace, a movable carriage mounted thereon, a draw bar pivotally mounted on the carriage, a pusher pivoted to the front of the carriage, a receptacle provided with a plane bottom having an aperture formed therein, a lug

having a groove formed therein secured to the bottom of the receptacle, the draw bar being adapted to engage the margin of the aperture formed in the receptacle and the pusher being adapted to engage the lug that is secured to the receptacle. 70

2. In a charging and discharging apparatus for a furnace, a frame mounted for lateral movement in front of the furnace, a movable carriage mounted thereon, a draw bar pivotally mounted on the carriage, a pusher pivoted to the front of the carriage, a receptacle provided with a plane bottom having an aperture formed therein, a lug having a groove formed therein secured to the bottom of the receptacle, the draw bar being adapted to engage the margin of the aperture formed in the receptacle and the pusher being adapted to engage the groove formed in the lug and power-operated means 80 for reciprocating the carriage. 85

3. In a charging and discharging apparatus for a furnace, a frame mounted on wheels for lateral movement in front of the furnace, a movable carriage mounted thereon, a draw bar pivotally mounted on the carriage, a pusher pivoted to the front of the carriage, a receptacle provided with a plane bottom and having an aperture formed therein, a lug having a groove formed therein which is secured to the bottom of the receptacle, the draw bar being adapted to engage the margin of the aperture formed in the receptacle and the pusher being adapted to engage the groove formed in the lug; power-operated 90 means for carrying the carriage forward and rearward and power-operated means for alternately pulling and pushing the receptacle. 95

4. In a charging and discharging apparatus for a furnace, a frame mounted on wheels for lateral movement in front of the furnace, a movable carriage mounted thereon, a draw bar pivotally mounted on the carriage, a pusher pivoted to the carriage, a receptacle provided with a plane bottom having an aperture formed therein, a lug having a groove formed therein secured to the bottom of the receptacle, the draw bar being adapted to engage the margin of the aperture formed in the receptacle, the pusher being adapted to engage the lug secured to the receptacle, power-operated means for moving the carriage to and fro, power-operated means for alternately pulling and pushing the receptacle and means for withdrawing the pusher mechanism from the furnace without moving or disturbing the receptacle. 105 110 115

5. In a charging and discharging apparatus for a furnace, a truck, power-operated means to move the truck laterally with respect to the front of the furnace, a frame mounted on the truck, a carriage mounted on the frame for reciprocation, a receptacle mounted on the frame, provided with an 120 125 130

- aperture and having a lug secured to the bottom thereof, power-operated means to engage the lug and push the receptacle within the furnace chamber and power-operated means to engage the margin of the aperture in the receptacle and pull the receptacle out of the furnace chamber. 5
6. In a charging and discharging apparatus for a furnace, a truck, power-operated means to move the truck laterally with respect to the front of the furnace, a frame mounted on the truck, a carriage mounted on the frame for reciprocation, a receptacle mounted on the frame, provided with an aperture and having a lug secured to the bottom thereof, power-operated means to engage the lug and push the receptacle within the furnace chamber, electric power controlled means to engage the margin of the aperture in the receptacle, power-operated means to stop the movement of the carriage at pre-determined points of its travel. 10
7. In a charging and discharging apparatus for a furnace, a truck, power-operated means to move the truck laterally with respect to the front of the furnace, a frame mounted on the truck, a carriage mounted on the frame for reciprocation, a receptacle mounted on the frame, provided with an aperture and having a lug secured to the bottom thereof, power-operated means to engage the lug and push the receptacle within the furnace chamber, power-operated means to engage the margin of the aperture and pull the receptacle, power-operated means to stop the movement of the carriage at pre-determined points of its travel and means to control the supply of electric current to the power-operated means. 15
8. In a charging and discharging apparatus for a furnace, a truck, power-operated means to move the truck laterally with respect to the front of the furnace, a frame mounted on the truck, a carriage mounted on the frame for reciprocation, a receptacle mounted on the frame, provided with an aperture and having a lug secured to the bottom thereof, power-operated means to engage the lug and push the receptacle within the furnace chamber, power-operated means to engage the margin of the aperture and pull the receptacle, power-operated means to stop the movement of the carriage at pre-determined points of its travel, means to supply an electric current to the power-operated means of the apparatus and controlling means for directing the flow of an electric current to a specific operating means of the apparatus at the will of the operator. 20
9. In a charging and discharging apparatus for furnaces, a wheeled truck, a frame mounted thereon, a carriage movable on the frame, power-operated means to impart movement to the carriage, a receptacle mounted on and movable on the frame, power-operated means to engage and push the receptacle in one direction and power-operated means to engage and pull the receptacle back to its normal position. 25
10. In a charging and discharging apparatus for furnaces, a wheeled truck, a frame mounted thereon, a carriage movable on the frame, power-operated means to impart movement to the carriage, a receptacle mounted on and movable on the frame, power-operated means to engage and push the receptacle in one direction, power-operated means to engage and pull the receptacle in an opposite direction and means to automatically stop the carriage. 30
11. In a charging and discharging apparatus for furnaces, a wheeled truck, a frame mounted thereon, a carriage movable on the frame, power-operated means to impart movement to the carriage, a receptacle mounted on and movable on the frame, power-operated means to engage and push the receptacle in one direction, power-operated means to engage and pull the receptacle back to its normal position, means to automatically stop the carriage, and means to supply an electric current to the apparatus. 35
12. In a charging and discharging apparatus for furnaces, a wheeled truck, a frame mounted thereon, a carriage movable on the frame, power-operated means to impart movement to the carriage, a receptacle mounted on and movable on the frame, power-operated means to engage and push the receptacle in one direction, power-operated means to engage and pull the receptacle back to its normal position, means to automatically stop the carriage, means to supply an electric current to the apparatus and means to control each specific operating means. 40
13. In a charging and discharging apparatus for furnaces, a truck, means to impart movement to the truck, a frame carried by the truck, a carriage mounted on the frame, a receptacle mounted on the frame, power-operated means to impart movement to the carriage, means attached to the carriage to engage and push the receptacle and means mounted on the carriage to pull the receptacle. 45
14. In a charging and discharging apparatus for furnaces, a truck, a carriage mounted for movement relative to the frame, a receptacle mounted on the frame, power-operated means to impart movement to the carriage, means attached to the carriage to engage and push the receptacle, means mounted on the carriage to pull the receptacle. 50
15. In an electrically-operated charging and discharging apparatus for furnaces, a truck, means to impart movement to the truck, a frame carried by the truck, a carriage mounted on the frame, a receptacle mounted on the frame, power-operated means to impart movement to the carriage, means 55

attached to the carriage to engage and push the receptacle, means secured to the carriage to pull the receptacle, means for collecting an electric current supply for operating the mechanism of the apparatus separately and controlling means mounted on the frame within the reach of the operator.

16. In a charging and discharging apparatus for furnaces, a combined truck and frame adapted to be moved laterally with respect to the front of the furnace, a movable carriage mounted on the frame of the truck, a receptacle having an aperture formed therein and a lug secured thereto and mounted on the frame, power-operated means to impart movement to the carriage, a projecting pusher member connected to the frame of the carriage which is adapted to engage and push the receptacle within the chamber of the furnace, and a draw bar having a hook formed at its end to engage the margin of the aperture formed in the receptacle and power-operated means to pull the receptacle out of the chamber of the furnace.

17. In a charging and discharging apparatus for furnaces, a combined truck and frame adapted to be moved laterally with respect to the front of the furnace, a movable carriage mounted on the frame of the truck, a receptacle having an aperture formed therein and a lug secured thereto mounted on the frame, power-operated means to impart movement to the carriage, a projecting pusher member connected to the carriage which is adapted to engage and push the receptacle within the chamber of the furnace, a draw bar having a hook formed at its end to engage the margin of the aperture formed in the receptacle, power-operated means to pull the receptacle out of the chamber of the furnace and means to supply an electric current to a particular pre-determined operating means of the apparatus.

18. In a charging and discharging apparatus for furnaces, a combined truck and frame adapted to be moved laterally with respect to the front of the furnace, a movable carriage mounted on the frame of the truck, a receptacle having an aperture formed therein and a lug secured thereto and mounted on the frame, power-operated means to impart movement to the carriage, a projecting member connected to the frame of the carriage which is adapted to engage and push the receptacle within the chamber of the furnace, a draw bar having a hook formed at its end to engage the aperture formed in the receptacle, power-operated means to pull the receptacle out of the chamber of the furnace, means to supply an electric current to a pre-determined operating means independent of the others and controlling means to direct the electric current to a particular mechanism.

19. In a charging and discharging appa-

ratus for furnaces, a truck adapted to be moved laterally with respect to the front of the furnace, a frame mounted thereon, a supporting member adapted to be moved forward and backward on the frame, power-operated means to impart movement to the supporting member, a receptacle having an aperture formed therein mounted for movement on the frame, power-operated means carried by the supporting member to engage the receptacle for pulling same, a push bar connected to the supporting member, a lug secured to the receptacle to engage the push bar to push the receptacle and power-operated means to impart movement to the carriage.

20. In a charging and discharging apparatus for furnaces, a truck, a frame mounted thereon, a carriage movably mounted on the frame, a receptacle mounted on the frame, a push bar connected to the carriage and adapted to push the receptacle within the chamber of the furnace, a draw bar adapted to engage with and pull the receptacle out of the chamber of the furnace.

21. In a charging and discharging apparatus for furnaces, a truck, a frame mounted thereon, a carriage movably mounted on the frame, a receptacle mounted on the frame, a push bar connected to the carriage and adapted to engage with and push the receptacle within the chamber of the furnace, a draw bar adapted to engage with and pull the receptacle out of the chamber of the furnace, power-operated means for imparting movement to the carriage and means within reach of the operator to control all operations of the apparatus.

22. In a charging and discharging apparatus for furnaces, a truck, a frame mounted thereon, a carriage movably mounted on the frame, a receptacle mounted on the frame, a push bar connected to the carriage and adapted to push the receptacle within the chamber of the furnace, a draw bar adapted to pull the receptacle out of the chamber of the furnace, power-operated means for imparting movement to the carriage and power-operated means to actuate the draw bar.

23. In a charging and discharging apparatus for annealing furnaces, a truck, a frame mounted thereon, a carriage movably mounted on the frame, a receptacle mounted on the frame, a push bar connected to the carriage and adapted to push the receptacle within the chamber of the furnace, a draw bar adapted to pull the receptacle out of the chamber of the furnace, power-operated means for imparting movement to the carriage, power-operated means to actuate the draw bar, and means to supply an electric current to the operating elements of the apparatus separately and all being within the control of one operator.

24. In a charging and discharging appa-

- 5   28. In a charging and discharging apparatus for furnaces, a combined frame and truck, a receptacle movably mounted on the frame provided with a lug and also having an aperture provided therein, a carriage mounted on the frame, means on the carriage to engage the receptacle for pulling same, means connected to the carriage and adapted to push the receptacle. 45
- 10   25. In a charging and discharging apparatus for annealing furnaces, a combined frame and truck, a receptacle movably mounted on the frame provided with a lug and also having an aperture provided therein, a carriage mounted on the frame, a draw bar mounted on the carriage and adapted to engage the receptacle for pulling same, a push bar connected to the carriage and adapted to engage with and push the receptacle and power-operated means to impart movement to the carriage. 50
- 15   26. In a charging and discharging apparatus for furnaces, a combined frame and truck, a receptacle movably mounted on the frame provided with a lug, and also having an aperture provided therein, a carriage mounted on the frame, a draw bar adapted to engage the receptacle for pulling same, a push bar connected to the carriage and adapted to push the receptacle, power-operated means to impart movement to the carriage and power-operated means to actuate the draw bar. 55
- 20   27. In a charging and discharging apparatus for furnaces, a combined frame and truck, a receptacle movably mounted on the frame provided with a lug and also having an aperture provided therein, a carriage mounted on the frame, a draw bar adapted to engage the receptacle for pulling same, a push bar connected to the carriage and adapted to push the receptacle, power-operated means to impart lateral movement to the truck and frame. 60
- 25   28. In a charging and discharging apparatus for furnaces, a truck and a frame, a carriage and receptacle mounted on the frame, engaging devices of a push and pull type mounted on the carriage and adapted to push the receptacle within and withdraw the receptacle from the chamber of a furnace, the carriage and push and pull mechanism being operated by power. 65
- 30   29. In a charging and discharging apparatus for furnaces, a truck and a frame, a carriage and receptacle mounted on the frame, engaging devices of a push and pull type mounted on the carriage and adapted to push the receptacle within and withdraw the receptacle from the chamber of a furnace, the carriage and push and pull mechanism being operated by power. 70
- 35   30. In a charging and discharging apparatus for furnaces, a truck and a frame, a carriage and receptacle mounted on the frame, engaging devices of a push and pull type mounted on the carriage and adapted to push the receptacle within and withdraw the receptacle from the chamber of the furnace, the carriage and push and pull mechanism being operated by power and means to impart lateral movement to the truck and frame. 75
- 40   31. In a charging and discharging apparatus for furnaces, a truck and a frame, a carriage and receptacle mounted on the frame, engaging devices of a push and pull type mounted on the carriage and adapted to push the receptacle within and withdraw the receptacle from the chamber of a furnace, the carriage and push and pull mechanism being operated by machine power, power means to impart lateral movement to the truck with respect to the front of the furnace and means for collecting an electric current for the operating means of the apparatus. 80
